WALL MOUNTED POWER AND CONTROL UNIT FOR AN AERATED BATH MAT

Willis A. Stageberg, St. Louis Park, Minn., assignor to
Louise Ideas, Inc., St. Paul, Minn., a corporation of
Minnesota, and C. Verner Gustafson, St. Paul, Minn.

Filed Feb. 5, 1968, Ser. No. 10,441

Term of patent 14 years

(Cl. D83—1)

FIG. 1 is a front, right side and top perspective view of the unit showing my new design.

FIG. 2 is a left side elevation.

FIG. 3 is a front elevation.

FIG. 4 is a top plan view.

FIG. 5 is a bottom plan view.

The broken lines are shown for illustrative purposes only.

I claim:

The ornamental design for a wall mounted power and control unit for an aerated bath mat, as shown and described.
